(57) **CLAIM**

The ornamental design for a mobile phone, as shown and described.

DESCRIPTION

FIG. 1 is a front view of the mobile phone showing our new design.

FIG. 2 is a rear view of the mobile phone of FIG. 1.

FIG. 3 is a left side view of the mobile phone of FIG. 1.

FIG. 4 is a right side view of the mobile phone of FIG. 1.

FIG. 5 is a top view of the mobile phone of FIG. 1.

FIG. 6 is a bottom view of the mobile phone of FIG. 1.

FIG. 7 is a top, front, and right perspective view of the mobile phone of FIG. 1; and,

FIG. 8 is a rear, bottom, and left perspective view of the mobile phone of FIG. 1.

The shade lines in the figures show contour and not surface ornamentation.

The broken lines in the figures show portions of the mobile phone and environment that form no part of the claimed design.

1 Claim, 6 Drawing Sheets
